UNITED STATES PATENT OFFICE

LEON R. MACKENZIE, OF DES MOINES, IOWA

METHOD OF MAKING A WEAR COURSE FOR PAVEMENTS

Application filed August 6, 1928. Serial No. 297,634

The purpose of my invention is to provide a simple and effective method for making a wear course for pavements.

My pavement is of the type which retains its plasticity by reason of the fact that it has a substantial content of asphalt, bitumin, or other suitable material. Such pavement when of substantial thickness has ordinarily movement within itself when subjected to traffic 10 and temperature conditions. This is true, even though it have a substantial rock aggregate content.

It is well known that during the summer months when the air temperature is quite high 15 that asphaltic materials, from which the wear course of a pavement is ordinarily formed, are subjected to easy displacement due to traffic upon the wear course.

The asphaltic materials during the high 20 temperature of the summer months are comparatively soft or pliable and due to traffic thereon are very quickly and easily displaced.

It is further well known that asphaltic materials have a greater affinity for heat and the 25 retention of the same. It thus follows that the heat which is absorbed within the pavement will give to the pavement a temperature greater or higher than the air temperature.

The degree of heat within the pavement is 30 retained for a considerable length of time after the sun's heat rays have been absorbed, and it is my object to provide a pavement that will eliminate the movement of the asphaltic material within itself.

It is therefore more particularly my purpose to provide a method for constructing such a pavement whereby any substantial movement within the body of the pavement 35 itself is eliminated.

Especially, it is my purpose to provide a method for making such a pavement having near the location therein at which such movement is ordinarily noticeable, a substantially 40 horizontal binding mesh anchoring means and

forcing rock aggregate, into the interstices of the anchoring means, a portion of the rock being of such size that upon compression of the pavement some of the rock will enter and project through all of the openings of the anchoring means. 50

It is quite generally recognized that for almost all sorts of pavement bases, and especially for the repair of worn concrete and brick pavement, the most efficient and generally 55 satisfactory top or wear course is of asphaltic or bituminous or other material which retains its plasticity during a relatively long life.

Heretofore as explained in my Patent Number 1,707,939, issued April 2, 1929, the use of 60 such material for a wear course has been in the face of certain well recognized difficulties and defects.

The asphaltic or bituminous material is 65 hard to keep in place. It tends to shift or roll and form humps and hollows. On a crowned road and especially under heavy traffic in warm weather, it tends to flow toward the low sides of the road, so that in time it will be much thicker at the sides of the road than in 70 the traffic lanes. Where high or low spots or humps and hollows are formed, the top course may ultimately form small holes, and water gets into the holes or seeps under the top course and greatly increases the rapidity with 75 which the pavement wear course deteriorates and disintegrates.

The difficulties experienced on account of the movement of asphaltic or bituminous top courses have greatly increased during recent 80 years on account of the universal use of motor vehicles. The stopping and starting of motor vehicles and the heavy impact from them tends to pull or push the upper surface of the plastic wear course for moving it out of its 85 original formation in the manner already referred to.

While highway engineers have for years 90 recognized the evils in the movement of plastic wear courses, they have not been able to solve

the problem of keeping the top course in its place.

It has often been thought that the difficulty might be cured by finding some means for anchoring the top or wear course to the base and for this purpose various kinds of interlocking and anchoring means have been provided.

The anchoring of the top course to the base, however, has not solved the difficulty, because of the fact that such top courses have movement within themselves, when of proper thickness as required to meet traffic conditions. Therefore, even though the lower part of the wear course may be anchored to the base, it is found that the upper part of such course has movement with relation to the lower part of the course with the resultant formation of high and low spots and "flow" toward the lower portions of the highway.

My experiments have shown me that there is a normal axis of movement of such wear courses within themselves. For instance, with certain asphaltic materials commonly in use, this axis of movement begins at about an inch from the bottom of the course. At an inch and a half from the bottom, it can be studied, and at from two inches and up, it is very noticeable.

In a two inch top course, even though the lower part of the course be anchored to the base, there will be movement in the material of the top course itself in that portion, which is for instance more than an inch above the bottom.

Efforts have also been made to cure the difficulty by using chemical ingredients for hardening the plastic material, but they have had only indifferent success.

It has been found that it is desirable to use a plastic top course of asphaltic or bituminous material, which does not have such normal movement within itself. When a wear course is laid thin enough so that it does not have such movement within itself, it becomes too thin for practical use. This is due to the fact that asphaltic materials have in them volatile oils, which are drawn out by hot weather, leaving a coke-like substance, which quickly disintegrates and pulverizes under traffic.

Therefore in order to secure sufficient longevity and wearing quality, it is necessary to use a top course so thick that it has movement within itself.

By the process of my present invention, I am able to provide an asphaltic or bituminous wear course in which this movement within the body of material itself is eliminated or so nearly eliminated as to be negligible for practical purposes.

For purposes of illustration, I have filed drawings herewith, in which:

Figure 1 is a perspective view partly in

section showing a lower layer, a metal reinforcing, and an upper layer, used in the practice of my process for making improved pavement.

Figure 2 is a vertical, sectional view through a portion of such pavement, illustrating at the left-hand part of the figure the complete pavement when first laid, and in the right-hand part of the figure the pavement after it has been rolled or otherwise compressed.

Figure 3 shows a perspective view of a section of the foraminous reinforcement which may be used in the practice of my method.

In carrying out my method, as by way of example, I lay upon worn-out concrete pavement or other pavement to be re-surfaced or upon any suitable base, such as water-bound macadam, rolled gravel, concrete or bituminous mixtures, a lower layer of asphaltic or bituminous mixture, containing standard materials and having therein fine sands and angular rock or stone, by way of example, sized from one fourth to one and one-fourth inches in their greatest dimensions.

This layer is preferably about one and one-quarter inches thick when fluffed to the contour of the highway. The thickness, of course, may vary somewhat depending upon the materials used and upon the height of the normal axis of movement in such material. It should be of such thickness that its top will not be much above the height where movement in a body of plastic top course begins within itself.

The base upon which the pavement is laid is indicated at 10, the lower layer of plastic material is indicated at A, and the rock therein by the reference numeral 12.

The greatest dimension of a portion of the rock should be greater than the thickness of the layer after the layer has been finally rolled.

Asphaltic mix or bituminous mix or natural rock asphalt may be used for the purpose.

Where hot asphalt is used, and wherever the process will permit, this lower layer A should be fluffed while hot and immediately there should be placed thereon sheets of expanded metal or other binding mesh anchoring means, such as indicated at 14. The sections thereof should be locked at their ends in any suitable way for making a continuous mat of this reinforcing.

Immediately a second layer B is imposed upon the reinforcing and the lower layer A thereunder.

The top layer B may be of the same material as the lower layer or may vary somewhat. It should contain stone, some of which is preferably of a largest dimension greater than the thickness of this top layer B after such layer has been rolled.

The product thus far completed is then subjected to pressure, as for instance by being rolled by heavy rollers. This pressure compacts and compresses the material, which is porous, and forces therefrom the air in its voids, and adjusts the rock, and in particular forces the rock from above and below the reinforcing downwardly and upwardly into and partially through the interstices of the reinforcing.

The size of the openings in the mesh may be for example six to twelve inches long dimensions, and three to six inches short dimensions (inside measurements). The mesh should be such with relation to the stone that several stone may enter the interstices and become fixed therein and can not have much lateral movement without coming into contact with the metal.

There is thus provided a solid mass in which the lower layer, upper layer and reinforcing are thoroughly tied or anchored together by rocks projecting into and through the meshes of the reinforcing.

In a pavement so made, the so-called axis of movement is raised to a point so near the top of the wear course as to be a negligible factor.

The upper paint or squeegee coat may be used upon the completed wear course.

After this paint or squeegee coat has been worn down, the resultant wear course is practically a monolithic surface, containing high stone content for effectively meeting abrasion and wear, which stone content is thoroughly keyed to the semi-rigid metal mesh and thus serves to anchor and hold the body of material against any movement within itself.

Any tendency of the upper part of the body of material to move would be resisted by the engagement of the stone in the interstices of metal with the strands of the metal.

It should perhaps be mentioned that the reinforcing material should be in a plane parallel to the top surface of the wear course and should not project either upwardly or downwardly any substantial distance above or below the top of the bottom layer A, so that it will not interfere with the raking and fluffing of the top layer.

It must be laid after the bottom layer A has been laid, so it will not interfere with the placing and fluffing of that layer.

It is possible that my method be practiced with well known and generally available materials and equipment.

In my claims, I intend by the use of the terms "asphalt" or "bitumin" or their adjectival derivatives to include any plastic paving material suitable for such a pavement and normally having movement within itself under traffic and temperature conditions.

In any reference to reinforcing, I intend to cover any foraminous material adaptable to the purpose.

I claim as my invention:

1. A method of making a bituminous pavement comprising the superposing of one layer of asphaltic material upon another, with a semi-rigid binding mesh anchoring element placed between them, and compressing the mass, and thereby forcing into and partially through the meshes of the anchoring element rock aggregate, a substantial portion of which is of a maximum size greater than the thickness of either layer when the layers are finally compressed.

2. A method of making a bituminous pavement, comprising placing upon a suitable base a layer of asphaltic material containing a large content of rock aggregate, a substantial portion of which is of a largest dimension slightly greater than the thickness of the layer after final compression of such layer, the placing upon said layer of a semirigid substantially continuous binding mesh anchoring means, placing upon such anchoring means and lower layer an upper layer of asphaltic material, having a large content of rock aggregate, a substantial portion of which aggregate has a largest dimension slightly greater than the thickness of the upper layer when such layer is finally compressed, and subjecting said pavement to pressure for thereby compressing both layers and forcing members of the rock aggregate into and partially through the interstices of the anchoring means.

3. A method of making a bituminous pavement comprising placing upon a suitable base a layer of asphaltic material containing a large content of rock aggregate, a substantial portion of which is of a largest dimension slightly greater than the thickness of the layer after final compression of such layer, the placing upon said layer of a semirigid substantially continuous binding mesh anchoring means, placing upon such anchoring means and lower layer an upper layer of asphaltic material, and subjecting said pavement to pressure for thereby compressing both layers and forcing members of the rock aggregate into and partially through the interstices of the anchoring means.

4. A method of making a bituminous pavement comprising placing upon a suitable base a layer of asphaltic material, the placing upon said layer of a semirigid substantially continuous binding mesh anchoring means, placing upon such anchoring means and lower layer an upper layer of asphaltic material having a large content of rock aggregate, a substantial portion of which aggregate has a largest dimension slightly greater than the thickness of the upper layer when such layer is finally compressed, and subjecting said pavement to pressure for thereby compressing both layers and forcing members of the rock aggregate into and partially through the interstices of the anchoring means.

5. A method of making a bituminous pavement comprising placing a layer of asphaltic material upon a base, placing a semirigid binding mesh anchoring means upon said layer, superposing a second layer of asphaltic material upon the anchoring means and lower layer and compressing the layers and forcing into the meshes of the anchoring means rock aggregate of such size relative to the layers and the meshes that upon final compression of the pavement some of the rock will enter all the meshes and project therethrough into both layers.
